UNITED STATES PATENT OFFICE.

JAMES W. LESLIE, OF MELROSE, MASSACHUSETTS.

CURTAIN-POLE AND RING THEREFOR.

SPECIFICATION forming part of Letters Patent No. 631,726, dated August 22, 1899.

Application filed February 19, 1896. Renewed December 19, 1898. Serial No. 699,754. (No model.)

To all whom it may concern:

Be it known that I, JAMES W. LESLIE, of Melrose, county of Middlesex, State of Massachusetts, have invented an Improvement 5 in Curtain-Poles and Rings Therefor, of which the following description, in connection with the accompanying drawings, is a specification, like letters on the drawings representing like parts.

10 This invention relates to supporting-poles for portières, curtains, and the like and to the rings for use in connection with said pole.

Prior to my invention it has been customary to provide poles of this class with rings 15 having one or more rollers adapted to travel on the upper surface of the pole; but in practice much difficulty has been found in keeping the rings out of lateral contact with the pole as the rings are drawn along the pole, 20 this being largely due to the proximity of the upper portion of the ring or of the carrier therefor to the surface of the pole.

To obviate this difficulty, my present invention comprehends a pole provided at its 25 upper side with a longitudinal raised track, comprising a single rail or a "plurality" of rails, as they may be called, and preferably formed by raising or crimping the material with which the pole is covered, the ring or 30 rings traveling on the track, said rings being thus raised from the pole and maintained out of lateral contact therewith.

In connection with a pole embodying my invention I contemplate employing rings having shoulders or stops arranged at opposite 35 sides the raised track on the pole to prevent lateral movement of the rings on said track and with relation to the pole. These rings may also be provided with rollers to travel on 40 said track, although my present invention enables me to employ rings without rollers, yet capable of operation with as little friction or draft as the rings with rollers.

45 My invention also comprehends a novel manner of holding the ring-rollers in position.

In the drawings, Figure 1 is an isometric sectional view showing a pole, ring, and socket embodying my invention; Fig. 2, a side elevation, partially broken away, of the 50 parts shown in Fig. 1; Fig. 3, an isometric

view illustrating a modification of my invention, and Fig. 4 a sectional detail to be described.

In the embodiment of my invention selected for illustration and shown in the drawings, Figs. 1 and 2, the pole A is shown as composed of a core a, about which is rolled a brass or other suitable covering material a', the edges of which are shown as locked together in a longitudinal line at a², as is customary in covered poles used for this purpose at the present time.

In accordance with my invention I have provided the pole A at its upper side with a raised track b, shown as formed in and by the 65 covering material a', the latter being preferably crimped, folded, or rolled over a support or rod b'.

The ring c may be of any suitable or desired construction, it being herein shown as 70 provided at its top with a roller c' and preferably provided with stops c², formed in a suitable manner and arranged at opposite sides of the track b to prevent lateral vibration of the ring on its said track.

In accordance with my invention the roller c' of the ring is inserted in a novel manner, best understood by reference to Figs. 3 and 4, wherein the ring, of a construction similar to that shown in Figs. 1 and 2, is partially 80 broken away. The roller-journals c³ are journaled, respectively, in the enlarged ends of U-shaped clips c⁴, inserted from the top of the ring into a pocket c⁵, formed in the ring and shown as extended through to the inner 85 side of the ring, providing the stops c² referred to. The short or outer legs of these clips c⁴ are inserted from the top of the ring through slits c⁶ in the latter, and are afterward clenched at the under side, as shown 90 at c⁷, Fig. 3, by means of a hand-tool inserted from the inner side of the ring through an aperture c⁸ provided thereat. To insert the roller in the ring, one of the clips c⁴ is first clenched in position, as shown in Fig. 3, and 95 the roller placed in position with one of its journals in the bearing in said clip. The other clip is now inserted, as indicated in dotted lines, Fig. 3, and in full lines, Fig. 4, and when the hole in the clip is opposite the 100

end of the journal on the roller said clip is turned down into final position, causing the journal to enter the hole referred to in said clip, after which its short leg, which, when 5 the clip is turned down into the slits c^4 , is clutched as described, thus providing a convenient means for inserting and removing the rollers.

The socket which I contemplate using in 10 connection with my improved pole is illustrated at d , it being provided with a central opening to receive the end of the pole and recessed at d' at one side to receive the raised track on the pole, said track coöperating with 15 said recess to restrain the pole against lateral movement in its socket or sockets.

One of the principal advantages attained by the use of a raised track is that the rings coöperating with the pole may be provided 20 with stop-surfaces, as described, to act upon the track and prevent the ring vibrating laterally and thereby coming into contact with the sides of the pole, it having been found that this frequent contact of the traveling ring with the sides of the pole soon 25 mars and otherwise injures the pole, greatly disfiguring it. This lateral contact is also further obviated or prevented by reason of the raising of the ring or the part thereof 30 which is nearest the pole away from close proximity to the pole—in other words, the ring when arranged upon the pole is nearly or quite concentric to the pole, so that it must swing through a much greater distance 35 in either direction before contacting with the pole than is the case with a ring which at its upper side is supported close to the pole, while at its lower side it drops to a considerable distance away from the pole.

40 Another advantage derived by my invention is that the track, whether presenting one or more rails or lines of contact, presents such a small surface contact to the ring that a ring of the old construction, without rollers, may 45 be drawn along the pole with practically as little friction or resistance as is found with the roller-rings so commonly employed on ordinary cylindrical poles, this reduction of friction being also due to entire absence of 50 frictional contact of the ring with the pole.

55 In Fig. 3 I have shown the track as composed of a flat strip bent to present a pair of rails $e e$, the track being inserted in and held by the slit in the pole, which receives the edges of the covering material for the pole.

60 My invention is not limited to the particular embodiment herein shown, for it is evident the same may be varied without departing from the spirit and scope of my invention.

65 I claim—

1. The herein-described covered curtain-pole, having its covering material raised longitudinally of the pole and projecting radially therefrom at one side of the latter to present 65 a raised track, and a support interposed between the said covering material and pole

to support said raised track from within, substantially as described.

2. The combination with a curtain-pole provided with a raised track, of a ring adapted 70 to travel thereon, and provided with lateral stops to coöperate with said track to restrain the ring against excessive lateral movement, substantially as described.

3. The combination with a curtain-pole provided with a raised track, of a ring therefor provided with a roller adapted to travel on said track, and having lateral stops coöperating with said track, substantially as described. 75

80 4. The herein-described curtain-ring provided with a roller-receiving pocket, a roller therein, and bearing-clips independent of each other, for the ends of the roller, said clips being independently secured to the ring 85 and in which said roller is journaled, substantially as described.

5. The within-described curtain-ring provided with a pocket-opening at the side of the ring and providing stops as described, a 90 roller within said pocket and exposed at said opening, substantially as described.

6. The within-described curtain-ring provided with a pocket-opening at the inside of the ring and furnishing stops as described, a 95 roller within said pocket and exposed at said opening, and bearing-clips independent but secured to said ring and in which said roller is journaled, substantially as described.

7. The within-described curtain-ring provided with a pocket-opening at the exterior and interior of the ring, a roller arranged in said pocket and exposed through said interior opening, and bearing-clips inserted in said pockets from the outside of the ring and 105 in which said roller is journaled, said bearing-clips being provided with legs inserted through said ring and secured within the latter, substantially as described.

8. The within-described curtain-ring provided with a pocket-opening at the exterior and interior of the ring, a roller arranged in said pocket, bearing-clips inserted in said pocket and in which said roller is journaled, holding-legs on said clips inserted through 115 said ring and clenched inside the latter, and apertures opposite said clenched legs for insertion of a clenching-tool, substantially as described.

9. The within-described curtain-ring provided with a pocket-opening both at the exterior and interior of the ring, the exterior opening of said pocket being of sufficient size to admit of introduction of the roller, the interior opening of said pocket being of a 125 smaller size to expose a portion only of said roller, the roller, and bearings for and to retain the same in position in said pocket, substantially as described.

10. The within-described curtain-ring provided with a pocket-opening at the inside of the ring, the ends of said opening furnishing 130

stops as described, a roller within said pocket and exposed at and within said opening, and independent bearing-clips one at either end of said roller secured to said ring and in which said roller is journaled, substantially as described.

In testimony whereof I have signed my

name to this specification in the presence of two subscribing witnesses.

JAMES W. LESLIE.
